TROLLEY-BASE.

1,114,380.

Specification of Letters Patent.

Patented Oct. 20, 1914.

Application filed September 19, 1912. Serial No. 721,225.

To all whom it may concern:

Be it known that I, WILLIAM J. PAUL, a citizen of the United States, residing at Everett, county of Middlesex, State of Massachusetts, have invented a certain new and useful Improvement in Trolley-Bases, of which the following is a specification, reference being had therein to the accompanying drawings.

10 My invention relates to a base to support the trolley pole of an electric car, in such a manner that the trolley will be yieldingly pressed against the underside of the trolley wire and may be capable of lateral movement as required. Heretofore difficulty has been experienced with trolley bases because the pressure exerted by the trolley on the wire reacts on the trolley base in such a manner as to cause the parts to cramp and bind and therefore to wear out rapidly.

15 A trolley base embodying my invention is so constructed that the pressure is transmitted substantially symmetrically, the center of pressure being about in line with the axis 25 of rotation of the trolley stand. The trolley base is also constructed so that rain cannot enter the bearings.

20 Furthermore by a peculiar arrangement of springs which will be later fully described a more lively trolley is produced, that is one which will follow any inequalities in the trolley wire quickly so that arcing is reduced to a minimum.

25 A trolley base and stand embodying my invention is lighter than those heretofore constructed, and is exceedingly durable, requiring little or no care. It is also so constructed that it projects only a little above the top of the car, thereby requiring less head room in subways, carbarns and under bridges.

30 The invention will be understood from the following description taken in connection with the accompanying drawings, and the 45 novel features thereof are pointed out and clearly defined in the claims at the close of this specification.

35 Referring to the drawings, Figure 1 is a side elevation of a trolley base and stand embodying my invention. Fig. 2 is a top plan view of the device shown in Fig. 1. Fig. 3 is a section on line 3—3 Fig. 1.

40 At 11 is shown the base which is secured by bolts to the roof of the car. Said base

has formed integral with it a spindle 12 around the circumference of which are placed rollers 13 forming a bearing for a hollow cap 14 to which the trolley stand 15 is secured. The balls 16, interposed between the top of the spindle 12 and the top 60 of the hollow cap 14, afford an anti-friction thrust bearing for said cap, while the rollers 13, interposed between the sides of said spindle and the side walls of said cap, afford an anti-friction side bearing for said 65 cap. The fact that the trolley stand extends from the cap at a point near the base thereof, and mainly below the bearing afforded by the rollers 13, gives the structure great stability. In practice, I find it desirable to 70 cast the cap 14 and the member 15 in a single piece. The downward thrust of the cap 14 on the spindle 12 is taken by means of a series of balls 16 running in a groove on the top of the spindle 12. It will be seen 75 that the cap 14 covers the working parts of the bearing so that it is impossible for rain to drive in and cause corrosion of the bearing. The cap 14 is prevented from jumping or being lifted off by means of two 80 retaining screws 17, 17, which project into a groove 18 in the spindle 12. The interior of the spindle is preferably hollow as shown at 19, and there are a series of holes 20 passing through the wall so that the cavity 19 85 may be packed with grease or vaseline, and the lubricant will gradually work through the holes and keep the rollers 13 lubricated. Said grease is conveniently inserted by removing a plug 21 in the top of the cap 14. 90

45 The trolley arm 25 is secured in the well known manner to one end of a bent member 26, known in practice as the cam. Said cam 26 is pivoted at its lower end as shown at 27 to the stand 15, said pivot 27 being on the 95 side of the spindle 12 opposite to the trolley pole and at a point considerably removed from the cap 14, thus bringing the connection between said cam and stand so far from the vertical axis of the stand as to afford 100 such leverage as will insure an easy turning movement of the stand on its vertical pivot or axis. With the cam 26 (which supports the trolley arm or trolley pole 25) thus pivoted to the trolley stand 15 at a point considerably removed from the vertical axis of the cap 14, and thus at some distance from the axis of movement of the said trolley

stand rigid or integral with said cap, there is considerable downward and lateral strain on said cap which is well taken care of by the horizontal anti-friction bearing for said cap afforded by the balls 16 and by the vertical anti-friction bearing for said cap afforded by the roller 13 and which balls and rollers are interposed between said cap and the hollow spindle 12.

10 The cam 26 is forked as is seen in Fig. 2, so that when the trolley arm is pulled down it will not interfere with the cap 14. Therefore the trolley pole may be depressed to a point below the level of the top of the cap. 15 A rod 28 located at an angle of the bent portion of the cam 26 forms the means of engagement for the trolley springs 31, 32, 33 and 34. The other end of said springs is secured to the transverse portion of a T-shaped member 35, the longitudinal portion of which is provided with adjusting nuts 36 and 37 which engage a lug 38 on the end of the stand 15. The two outside springs 31 and 34 are preferably made of slightly 20 coarser wire than the two inside springs 32 and 33 so that the inside springs are somewhat longer, or contain more coils, than the outside springs. This construction is such that when the trolley wheel is depressed by 25 a low place in the wire the two outside springs 31 and 34 increase the force applied to the pole. It results from this construction that the trolley follows the wire better at high speeds and arcing is prevented. 30 35 This construction results in what is commonly termed a lively trolley, that is one which follows all the inequalities in the wire. At 40 is shown a stop with which the cam 26 contacts when the trolley leaves the 40 wire.

By reference to Fig. 1 it will be seen that the cam 26 is so bent or formed that one portion thereof is disposed at an obtuse angle to the other portion, forming an elbow, 45 and that the rod 28, to which the pull springs 31, 32, 33 and 34 are connected, is located at the angle of the elbow or where the two bent portions meet. As this angle of the elbow is some distance above the pivot 50 of the cam and trolley arm the stress of the said springs is most advantageously applied so as to contribute to the "lively" action of the trolley, as above referred to. In other words, while the pull of the springs is 55 in a direction which is practically at a right

angle to the lower arm of the bent trolley cam, this pull is in a direction at an obtuse angle to the upper arm thereof. Also by having the trolley stand secured to or extending from the tubular member or cap 14 60 near the base thereof a very stable construction is afforded.

What I claim is;

1. An improved trolley support consisting of the combination with a base having an upwardly projecting hollow spindle provided with lateral openings for the outward passage of a lubricant contained in the chamber of said spindle, of a cap fitting over said spindle and provided with a trolley stand extending horizontally from a point near the base of said cap and thus affording stability, a horizontal anti-friction bearing between said cap and the top of said spindle, a vertical anti-friction bearing 75 between the sides of said cap and said spindle and lubricated from the chamber of the latter, means for retaining said cap on said spindle, a trolley cam pivoted to said trolley stand at a point which is at a substantial 80 distance from said cap and thus affording considerable leverage the strain of which is taken care of by said horizontal and vertical bearings, and springs connecting said trolley cam with said trolley stand.

2. An improved trolley support consisting of the combination with a base having an upwardly projecting spindle of a cap fitting over said spindle and provided with a trolley stand extending horizontally from a point near the base of said cap and thus affording stability, a horizontal anti-friction bearing between said cap and the top of said spindle, a vertical anti-friction bearing between the sides of said cap and said spindle, means for retaining said cap on said spindle, a trolley cam pivoted to said trolley stand at a point removed from said cap and thus affording considerable leverage the strain of which is taken care of by said horizontal and vertical bearings, and two sets of springs of different gage wire and unequal numbers of coils connecting said trolley cam with said trolley stand.

In testimony whereof I affix my signature, 105 in presence of two witnesses.

WILLIAM J. PAUL.
